ADOLPH M. HOLSTEIN, OF SYRACUSE, NEW YORK.

DESIGN FOR A GRILL FOR PHONOGRAPH-CABINETS.

56,813.

Specification for Design.

Patented Dec. 28, 1920.

Application filed November 15, 1919. Serial No. 338,388. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Grill for Phonograph-Cabinets, of which the following is a specification, reference being had to the accompanying drawing, forming a part hereof, which is a face view of this grill for phonograph-cabinets.

I claim:

The ornamental design for a grill for phonograph cabinets, substantially as shown.

In testimony whereof, I have hereunto signed my name, at Syracuse, in the county of Onondaga, and State of New York, this 8th day of November, 1919.

ADOLPH M. HOLSTEIN.
